UNITED STATES PATENT OFFICE.

BURTON S. ELLS, OF TROY, NEW YORK.

COLLAR.

No. 927,134.

Specification of Letters Patent.

Patented July 6, 1909.

Application filed September 2, 1908. Serial No. 451,342.

To all whom it may concern:

Be it known that I, BURTON S. ELLS, a citizen of the United States, and a resident of Troy, in the county of Rensselaer and State of New York, have invented a new and Improved Collar, of which the following is a full, clear, and exact description.

This invention relates to collars, and particularly to what are known as fold collars or turned down collars.

The object of the invention is to provide a collar of this class having improved means for attaching the same to the collar button at the back of the neck band, and which will operate to prevent the collar button at this point from coming in contact with the cravat or necktie which may be worn with the collar.

The invention consists in the construction and combination of parts, to be more fully described hereinafter and particularly set forth in the claim.

Reference is to be had to the accompanying drawings forming a part of this specification, in which similar characters of reference indicate corresponding parts in all the views.

Figure 1 is a perspective of a collar constructed according to my invention; Fig. 2 is a plan showing the middle portion of a collar laid flat as though resting upon a table or ironing board; and Fig. 3 is a vertical section taken at the back of the collar and showing a portion of the neck band of a shirt to which the collar is attached; this view shows how the collar is held to the neck band without permitting the stud or collar button to come in contact with the necktie.

Referring more particularly to the parts, 1 represents the collar, which may be of the fold form, as shown, having an inner band 2 and a top or turned over portion 3 attached to the same at the upper edge of the collar. At the middle of the collar and at the back I provide a flap 4. This flap is formed integral with the inner band 2 and projects 45 beyond the lower edge of this band when the collar is being formed, as indicated in Fig. 2. In order to complete the collar the flap 4 is folded upwardly on the dotted line 6, which constitutes a continuation of the lower edge 50 5, until the flap comes into substantially the

position shown in Figs. 1 and 3, that is, the flap projects upwardly. In this position it is further secured to the band 2 by stitching or sewing 7, applied parallel with the lower edge 5 and adjacent thereto. At a suitable 55 point the flap 4 is provided with a button-hole 8 which is adapted to be received over the collar button 9 at the rear of the neck band 10 of the shirt, in the manner indicated in Fig. 3. When the collar is applied in this 60 way it will be seen that the inner band 2 comes between the end of the collar button 9 and the cravat or necktie 11, which is represented in the space between the inner band and the top 3. By forming the flap 4 integral 65 with the inner band 2, the strength and durability of the flap is much increased, and the cost of production of the collar is decreased on account of the fact that the flap may be formed on the inner band when the collar is 70 cut from the stock. The stitching 7 increases the securesness of the flap and also holds it in its upwardly projecting position, which brings the buttonhole 8 opposite the stud. Although the flap 4 is made integral 75 with the inner band 2, it is preferably of fewer plies of material than the inner band. In this way its effectiveness may be increased and undue bulkiness at this point of the collar obviated.

Having thus described my invention, I claim as new and desire to secure by Letters Patent:

A collar of the class described, having a band with an integral flap formed thereupon at the lower edge thereof, said flap projecting upwardly on the inner side of said band, and means for attaching said flap to said band at a point above the lower edge of said band, said flap having a buttonhole adapted 85 to receive a collar button at the back of the neck band.

In testimony whereof I have signed my name to this specification in the presence of two subscribing witnesses.

BURTON S. ELLS.
